UNITED STATES PATENT OFFICE.

JOHN W. MORRIS, OF KILA, MONTANA.

LOCKING DEVICE FOR SAWMILL-DOGS.

1,139,055.

Specification of Letters Patent. Patented May 11, 1915.

Application filed September 30, 1913. Serial No. 792,653.

To all whom it may concern:

Be it known that I, JOHN W. MORRIS, a citizen of the United States, residing at Kila, in the county of Flathead and State 5 of Montana, have invented a new and useful Locking Device for Sawmill-Dogs, of which the following is a specification.

The invention relates to a locking device for saw mill dogs.

10 The object of the present invention is to provide a simple, inexpensive and efficient resilient locking device of strong and durable construction, adapted to be readily applied to various makes of head blocks in 15 common use, and capable of securely holding the operating lever of a saw mill dog in an elevated position when the same is not in use.

With these and other objects in view, the 20 invention consists in the construction and novel combination of parts hereinafter fully described, illustrated in the accompanying drawing, and pointed out in the claims here-to appended; it being understood that various changes in the form, proportion, size 25 and minor details of construction, within the scope of the claims, may be resorted to without departing from the spirit or sacrificing any of the advantages of the invention.

30 In the drawing:—Figure 1 is a side elevation of a saw mill dog equipped with a resilient locking device, constructed in accordance with this invention. Fig. 2 is an end elevation partly in section. Fig. 3 is a 35 perspective view of the resilient locking device.

Like numerals of reference designate corresponding parts in all the figures of the drawing.

40 In the accompanying drawing in which is illustrated the preferred embodiment of the invention, the resilient locking device comprises in its construction a spring actuated latch lever 1 and a supporting bar 2, ar- 45 ranged at an inclination and having a lower attaching portion secured by bolts 3 and 4 or other suitable fastening devices to a knee 5. The supporting bar 2 carries at its upper end a laterally extending arm 6, provided at 50 its inner terminal with an attaching flange 7 and having an opening 8 at the outer end through which passes a screw 9. The flange 7 is riveted or otherwise secured to the upper end of the supporting bar 2, but the arm

may be fixed to the same in any other suitable manner or be formed integral therewith.

The screw, which is provided at its upper end with a head, has a threaded lower end portion 10, which receives a milled nut 11 for varying the tension of a coiled spring 12 disposed on the screw and interposed between the arm and the latch lever 1. The latch lever 1, which is constructed of suitable metal, is arranged at an inclination in spaced relation with the supporting bar and is provided at its lower end with a laterally extending portion 13, and it has an arm 14 projecting upwardly from the laterally extending portion 13 and pivoted at its upper terminal to the supporting bar by the bolt 4. The other end of the latch lever is bent to form an approximately triangular loop 15 constituting a head and consisting of angularly disposed inner and outer portions 16 and 17 and a top portion 18 having a perforation 18^a through which the screw passes. The inner portion 16 is disposed at nearly a right angle to the body portion of the latch lever 1 and forms a shoulder for 80 engaging a laterally extending pin 19 of an operating lever 20 of a saw mill dog, and the outer portion 17 which extends upwardly at an acute angle is arranged at an inclination and presents a lower inclined 85 face adapted to be engaged by the said pin 19 when the operating lever is swung upwardly to the position illustrated in Fig. 1 of the drawing. The pin is adapted to lift the head of the latch lever against the ac- 90 tion of the coiled spring and to pass beneath the head and into engagement with the shoulder at the inner end thereof. The milled nut enables the tension of the spring to be adjusted. The resilient locking device 95 is adapted to be applied to various makes of saw mill dogs, and owing to the strength and durability of the construction, it is not liable to be easily broken or get out of order. Should the coiled spring become broken or 100 otherwise defective, it may be readily replaced by a new spring. The device may be made either right or left hand to enable it to be arranged at either side of a knee.

What is claimed is:—

1. The combination with a relatively fixed support and a pivotally mounted operating lever provided with a lateral projection, of

105

a supporting bar secured to the said support and projecting therefrom, a latch lever arranged below and in spaced relation with the supporting bar and pivotally connected at one end with the same, said latch lever being provided at the other end with a downwardly projecting head arranged to engage with the lateral projection of the operating lever, and a spring interposed between the supporting bar and the latch lever and arranged to urge the latter downwardly.

2. The combination with a relatively fixed support and a pivotally mounted operating lever provided with a lateral projection, of an inclined supporting bar secured at its lower end to and projecting from the said support and provided at its upper end with a lateral extension, an inclined latch lever arranged below and in spaced relation with the supporting bar and provided at its upper end with a head adapted to engage with the lateral projection of the operating lever, said latch lever having its lower end bent laterally toward the support and provided with an upwardly extending arm pivoted to the lower end of the supporting bar, and slidable means connected with the laterally extending arm of the supporting bar and

with the head of the lever for urging the latter downwardly.

3. The combination with a relatively fixed support and a pivotally mounted operating lever provided with a lateral projection, of a supporting bar secured at one end to the support and pivoted to the attached end of the same, said latch lever having its other end portion bent downwardly at approximately a right angle and then upwardly at an acute angle to substantially the plane of the latch lever and then bent inwardly to the same, forming an approximately triangular head adapted to engage with the lateral projection of the operating lever, a rod piercing the supporting bar and the inwardly bent portion of the head of the latch lever and constituting a slidable connection between the said latch lever and bar, and a coiled spring disposed on the rod and arranged to urge the lever downwardly.

In testimony, that I claim the foregoing as my own, I have hereto affixed my signature in the presence of two witnesses.

JOHN W. MORRIS.
